DESIGN FOR AN ASH TRAY OR THE LIKE

Eleanor R. Wood, Beverly Hills, Calif.

Application June 19, 1943, Serial No. 110,483

Term of patent 14 years

(Cl. D85—2)

To all whom it may concern:

Be it known that I, Eleanor R. Wood, a citizen of the United States, residing in Beverly Hills, in the county of Los Angeles and State of California, have invented a new, original, and ornamental Design for Ash Tray or the like, of which the following is a specification, reference being had to the accompanying drawing, forming part thereof.

Fig. 1 is a perspective view of an ash tray showing my new design; and

Fig. 2 is an end elevational view of the ash tray illustrated in Fig. 1.

I claim:

The ornamental design for an ash tray or the like, substantially as shown.

ELEANOR R. WOOD.
